UNITED STATES PATENT OFFICE.

KENNETH L. CURTIS, OF BOSTON, MASSACHUSETTS, ASSIGNOR TO ALBERT AND J. M. ANDERSON MANUFACTURING COMPANY, OF BOSTON, MASSACHUSETTS, A CORPORATION OF MAINE.

CIRCUIT-CONTROLLING APPARATUS.

1,294,411.

Specification of Letters Patent.

Patented Feb. 18, 1919.

Application filed April 15, 1916. Serial No. 91,452.

To all whom it may concern:

Be it known that I, KENNETH L. CURTIS, a citizen of the United States, and a resident of Boston, in the county of Suffolk and State of Massachusetts, have invented an Improvement in Circuit-Controlling Apparatus, of which the following description, in connection with the accompanying drawings, is a specification, like characters on the drawings representing like parts.

This invention relates to a circuit controlling apparatus of novel construction, which is especially designed and adapted for use as a reverse current relay, and is operated by a reversal of the current in the circuit to which the said relay is applied, said relay being designed to be used for protecting apparatus included in said circuit.

The invention has for its object to provide a reverse current relay which is highly sensitive and efficient in operation, is inexpensive to construct and is reliable in operation.

The particular features of this invention will be pointed out in the claims at the end of this specification.

Figure 1 is a side elevation of a reverse current relay embodying this invention.

Fig. 2, a rear end elevation looking toward the left in Fig. 1.

Fig. 3, a horizontal section on the line 3—3, Fig. 1, looking upward.

Fig. 4, an enlarged detail in section on line 4—4, Fig. 9.

Figs. 5, 6, 7 and 8, details of the magnetizable members.

Fig. 9, a detail in elevation looking toward the right in Fig. 1, and

Fig. 10, a detail in plan to be referred to.

Referring to the drawing *a*, *b*, represent two magnetizable members, which are spaced apart and arranged substantially parallel to each other and are magnetically connected at their upper ends as will be described.

Each of the members *a*, *b*, is made as herein shown as a substantially oblong frame comprising substantially parallel sides 10, 12, of unequal length, a cross bar 13 connecting said sides at their upper ends, and arms 14, 15, extended in substantially parallel planes from the lower ends of the

sides 10, 12, toward each other so as to have their ends overlap.

The sides 10, 12, cross bar 13, and arms 14, 15, of each frame or member *a*, *b*, are preferably composed of laminations or thin strips or sheets of steel, which laminations are fastened together by rivets 16 or otherwise, and the sides 10, 12, cross bar 13, and arms 14, 15, are preferably made separate from one another and suitably fastened together.

The ends of the arms 14, 15, form poles for the magnetizable members *a*, *b*, and the latter are reversely arranged, that is, with the short side 10 of one frame as *a* in the same vertical plane with the long side 12 of the frame *b*, and vice versa, so that the arms 14 are in the same horizontal plane and the arms 15 are in a horizontal plane below the plane in which the arms 14 are located, whereby the north pole of one magnetizable member as *a* is in the same horizontal plane with the south pole of the member *b*, and the north pole of the member *b* is in the same horizontal plane as the south pole of the member *a*. The members *a*, *b*, for the best results are metallically connected at their upper ends by steel bars or rods 20, which may be located at the ends of the cross bars 13, (see Fig. 10), and are secured to said cross bars and side bars 10, 12, by screws 21, the bars or rods 20 also serving as spacing bars for the members *a*, *b*.

The magnetizable members *a*, *b*, have cooperating with them an armature comprising a soft iron core 22, which is continuously magnetized by a coil 23, connected in circuit with a battery 24 or other extraneous source of direct current. The coil 23 is provided as shown with a covering 25 of insulation and is mounted on a center sleeve 26 of brass or other non-magnetic material, which is of larger diameter than the core 22, the latter being extended through said sleeve and secured as by screws 27 to a movable carrier, herein shown as an open frame 28, which is pivoted at 29 to a stationary frame 30, which latter is secured to the magnetizable members *a*, *b*. The sleeve 26 is stationary, and in the present instance, has its ends extended between the arms 14, 15,

of the members *a*, *b*, and rests upon the lower arms 15.

By means of the coil 23, the polarity of the armature or core 22 is maintained constant, that is, one end coöperating with the poles of one member as *a* is north and remains north, and the other end coöperating with the member *b* is south and remains south. The poles of the core 22 are marked 10 N S in Figs. 5, 6, 7 and 8.

The magnetizable members *a*, *b*, and the armature or core 22 constitute one form of relay, and the said armature is attracted in one direction by poles N S of the long arms 15, of the members *a*, *b*, as shown in Figs. 15 5 and 6, when a current is traversing in one direction the circuit to which the relay is applied, which circuit is represented by the laminated bus bar 32, which is extended 20 through the members *a*, *b*, and is separated therefrom by insulation 33, and said armature is repelled by said poles of the long arms 15 of the members *a*, *b*, and is attracted by the poles of the short arms 14, when the 25 current is reversed in the circuit represented by the bus bar.

In this latter case, the polarity of the poles of the members *a*, *b*, is reversed as indicated by N' S' in Figs. 7 and 8. When the 30 reverse current disappears from the circuit and the current again flows in its normal direction, the polarity shown in Figs. 7 and 8, is again changed to that shown in Figs. 5 and 6, and as soon as the reverse current disappears, the core 22 is lowered into its normal position shown in Figs. 5 and 6, which position is also that shown in Fig. 1, by a spring 61.

These movements of the armature or core 40 22 are utilized to control other apparatus by means of coöperating relay contacts, and in the present instance I have illustrated one construction or form of relay contacts which may be preferred by me. In the present instance the movable armature carrier or frame 28 has secured to it a movable contact member, preferably a carbon wheel or disk 35, which coöperates with two spring brushes or arms 36, 37 (see Fig. 9) constituting the 45 stationary contact member for the relay. The carbon disk 35 is loosely mounted upon a screw 38 (see Fig. 4), which is carried by a metal plate or upright 39 and retained thereon by a nut 40.

The metal plate 39 is secured to the front cross bar 41 of the armature frame or carrier 28 (see Figs. 3 and 9) by screws 42, which are separated by insulation 43 from said plate, and the latter is separated from 50 the metal frame 28 by insulation 44.

The spring arms or brushes 36, 37, have their lower ends located on opposite sides of the movable member 35 and are secured to the metal arms 50, 51, fastened as by screws 60 65 52 to the opposite ends of a block 53 of insu-

lating material, which block is fastened as by screws 54 to a cross bar 55 attached to or forming part of the stationary frame 30 (see Figs. 1 and 9.)

The brushes 36, 37 are provided with substantially straight and parallel arms, which engage the opposite sides of a lug or projection 56 on the insulating block 53 to hold the said brushes apart. To insure superior contact between the disk 35 and the brushes 36, 37, the latter may be provided with inclined portions 58 (see Fig. 9).

The relay contacts or brushes 36, 37, are included in a circuit represented by the wires 59, 60, Fig. 9, which circuit is closed 80 by the engagement of the contact member 35 with the contact brushes 36, 37.

Under normal conditions, namely, with current flowing in the proper direction in the circuit represented by the bus bar 32, 85 the relay contact 35 is disengaged from the contacts 36, 37, which is effected by the spring 61 connected with the rear end of the armature carrying frame 28, and the distance the relay contact 35 is separated from 90 the contacts 36, 37, is determined by a back stop or screw 62 (see Fig. 1) with which the front end of the armature carrying frame is engaged.

The rear end of the armature carrying 95 frame has coöperating with it a screw 63, which acts as a stop for the said frame and serves to limit the upward movement of the front end of the frame and thereby avoid injury to the contact brushes 36, 37, when 100 the contact member 35 is engaged therewith. The tension of the spring 61 may be regulated by adjusting nuts 163, 64, on a screw rod 65 to which the upper end of said spring is connected, and said spring is normally adjusted so as to lower the armature as soon as 105 the reverse current ceases to flow through the circuit represented by the bus bar 32.

The reverse current relay herein shown and described is designed to complete the 110 circuit 59, 60, whenever a reversal of current occurs in the circuit represented by the bus bars 32, so as to protect the electrical apparatus which could in any way be injured by a reversal in the direction of flow of the current in the circuit represented by the bus bar.

As an example of the use of the reverse current relay, the circuit represented by the bus bar, may include a circuit breaker or switch of known construction, which is provided with an electric tripping coil or device, and this coil or device is included in the circuit represented by the wires 59, 60. Under normal conditions, the circuit breaker is closed and held in its closed position by 115 the tripping device, but when for any cause a reversal of current takes place in the bus bar circuit, the reverse current relay acts to close the circuit of the tripping device, and the latter acts to permit the circuit breaker 120 125 130

to open the circuit represented by the bus bar, thereby preventing any apparatus connected with or included in said bus bar circuit from being injured by the reverse current.

The type of circuit breaker referred to is well known and it is deemed unnecessary to illustrate the same.

The armature or core 22 forms part of a magnetic circuit, which under normal conditions may be traced as follows: from the N pole of the core 22, Fig. 5, to S pole of member *a*; thence through the arm 15, side bar 12, cross bar 13, tie bars 20 to cross bar 13 of member *b* Fig. 6; thence by side bar 12 to N pole of arm 15; thence by S pole of core 22, back to N pole of the latter.

When the current is reversed, the magnetic circuit may be traced as follows:

From N pole of core 22, Fig. 7, to S' pole of member *a*, thence by arm 14, side bar 10, cross bar 13, tie bars 20, to cross bar 13 of member *b*, thence by side bar 10, arm 14, to pole N' of said arm, thence by S pole of core 22 back to N pole of the latter.

Inasmuch as a superior quality of steel is obtained in thin sheets or strips, a superior magnetic circuit and a more sensitive device is obtained by making the members *a*, *b*, in laminated form, and in addition the expense of construction is reduced.

Furthermore by making the armature or core 22 of soft iron and magnetized by a coil, which is included in an extraneous direct current circuit, the polarity of the core is maintained the same under all conditions of use, with corresponding effectiveness in the apparatus under all conditions of use.

I have herein shown one construction of apparatus embodying the invention, but it is not desired to limit the invention to the particular construction shown.

Claims:

1. In an apparatus of the character described, in combination, magnetizable members spaced apart and each comprising substantially parallel side bars, a cross bar connecting said side bars and arms extended from said side bars toward each other in different planes and having their free ends overlapped, means for magnetically tying said members together, an armature having the opposite ends of its core extended between the arms of said members, a coil surrounding said core and connected with a source of direct current, a movable carrier for said armature, a contact member connected with said carrier to move therewith, and a contact member coöperating with the contact member movable with said carrier.

2. In an apparatus of the character described, in combination, substantially parallel magnetizable members, each comprising an open frame having side bars of unequal length, a top cross bar, and arms ex-

tended toward each other from said side bars, the free ends of said arms constituting magnetic poles, magnetizable means connecting the substantially parallel frames at their upper ends, an armature extended from 70 frame to frame and having the ends of its core coöperating with the poles of said frames, a contact member movable with said armature, and a contact member coöperating with the first-mentioned contact member. 75

3. In an apparatus of the character described, in combination, a laminated magnetizable member provided with substantially parallel side bars of unequal length, a 80 cross bar connecting said side bars, and arms extended from said side bars in different planes toward each other to overlap, a second laminated magnetizable member of like construction and having its longer side bar 85 in substantially the same vertical plane as the shorter side bar of the first-mentioned member, means for magnetically connecting said magnetizable members, and an armature having its ends extended between the 90 overlapping arms of said magnetizable members.

4. In an apparatus of the character described, in combination, a laminated magnetizable member provided with substantially parallel side bars of unequal length, a cross bar connecting said side bars, and arms extended from said side bars in different planes toward each other to overlap, a second laminated magnetizable member of like 100 construction and having its longer side bar in substantially the same vertical plane as the shorter side bar of the first-mentioned member, means for magnetically connecting said magnetizable members, a stationary 105 frame secured to said magnetizable members, a frame surrounding said magnetizable members and pivoted to said stationary frame, an armature having its ends extended between the overlapping arms of said magnetizable members and connected with said pivoted frame, a contact member movable with said pivoted frame, and a contact member supported by said stationary frame and with which the first-mentioned contact member coöperates. 110

5. In an apparatus of the character described, in combination, a laminated magnetizable member provided with substantially parallel side bars, a cross bar connecting said side bars, and arms extended from said side bars toward each other, a second laminated magnetizable member of like construction arranged substantially parallel to the first-mentioned laminated magnetizable member, means for magnetically connecting said members together, an armature having its ends extended between the arms of said magnetizable members, and means movable with said armature. 120 125 130

6. In an apparatus of the character described, in combination, a magnetizable member provided with substantially parallel side bars, a cross bar connecting said side bars, and arms extended from said side bars toward each other, a second magnetizable member of like construction arranged substantially parallel to the first-mentioned magnetizable member, means for magnetically connecting said members together, an armature having its ends extended between the arms of said magnetizable members, and means movable with said armature.
- 10

7. In an apparatus of the character described, in combination, an electric conductor, substantially parallel open frames of magnetizable metal through which said conductor extends and having poles, means for magnetically connecting said frames together, an armature cooperating with said poles, and means movable with said armature.
- 15

In testimony whereof, I have signed my name to this specification.

KENNETH L. CURTIS.
